UNITED STATES PATENT OFFICE

EDGAR COCKS, OF LOS ANGELES, CALIFORNIA, ASSIGNOR TO LOS ANGELES WALL BED COMPANY, OF LOS ANGELES, CALIFORNIA, A CORPORATION OF CALIFORNIA

PORTABLE FOLDING BED

Application filed May 22, 1926. Serial No. 110,841.

This invention relates in a general way to bed constructions, and more specifically to folding beds, of the portable type, adapted to be stored, when not in use, within a closet or recess and moved therefrom into a room for use. This type of bed is commonly termed a "recess bed"; the particular objects to be attained being compactness and mobility.

The invention herein shown and described is somewhat similar to my inventions shown and described in two copending applications, one filed Dec. 3, 1925, Ser. No. 72,869 and the other filed Dec. 3, 1925, Ser. No. 72,870, both entitled "Folding beds". The invention of the instant case differs from the former, however, in certain specific details relating to the operation of the auxiliary leg and the means for preventing movement of the bed frame while the auxiliary leg is in folded or inoperative position.

The essential elements of a bed of this character include a base, movably supported upon rollers, and a bed frame pivotally mounted on the base to swing in a vertical plane; being disposed in vertical position on the base for storage or horizontally for use. When in horizontal position the frame overhangs one side; the base serving as a support for one end, the opposite end being supported on folding legs (not shown).

In order that the entire structure may occupy a minimum of storage space and be movable through standard width doors, the base is as small and compact as is permissible, consistent with its functional requirements; and to minimize the physical effort necessary to lower and raise the bed frame, balance or tension springs are provided between the inner swinging end of the frame and the base. These are of a strength sufficient to normally hold the frame in its vertically disposed position, but weak enough to be overcome by its unbalanced weight, to a certain extent, when it is moved towards the horizontal position for use. The bed frame is pivotally supported adjacent one of its ends on the base, and when the usual amount of bedding is placed thereon, its unbalanced weight is considerable. Consequently, the balance springs must have considerable tensile strength in

order to minimize the physical effort required to raise or lower the frame and bedding between the horizontal and vertical positions. As the aggregate tensile strength of the balance springs is greatest when the bed frame is in its horizontal position, and as this tension is increasing as the frame is being moved to this position from the vertical, its tendency is to tip the base in the same direction the frame is being moved, and this tendency is increased by the shifting of the center of gravity of the entire structure relative to the base. In order to counteract this tendency, either a great deal of undesirable weight must be added to the base, or it must be made of a plan area so large that it cannot be conveniently stored in comparatively small recesses or passed through standard width doors.

In view of these conditions, the invention of the instant case, as well as those of my aforementioned copending applications Ser. Nos. 72,869 and 72,870, has been conceived and perfected; my general object in each instance being to provide a simple and compact base structure, having one or more movable auxiliary supporting legs, arranged to be moved to folded position, when the frame is vertically supported on the base for storage, or moved to extended position when the frame is to be lowered to the horizontal for use.

With this arrangement a base of minimum plan area may be substantially increased when necessary to withstand the tension of the balance springs and obviate possibility of the base collapsing on the frame when the latter is moved to the horizontal, without sacrificing any of the desired compactness for storage or weakening the tensile strength of the balance springs to the point of requiring excessive physical effort in raising or lowering the bed frame.

As in my aforementioned co-pending application, Ser. No. 72,870, the present improvement is generally directed to means to prevent movement of the bed frame from the vertical towards the horizontal until the foldable auxiliary leg is moved to its extended position, thereby preventing possibility of

oversight and resulting in injury to the operator. I also provide a suitable latching arrangement to prevent accidental movement of the auxiliary leg from its extended position towards its folded position, such as might be done by its catching on the edge of a rug or the like when the bed is moved.

The particular distinction between the improvements of the instant case and those of my application Ser. No. 72,870 is that in this case a different curvature and upward tilt is given to the locking arm to an extent sufficient to not only insure the auxiliary leg being fully extended before the bed frame can be moved towards the horizontal to an unbalanced position on the base, but to also insure the bed frame being always moved from the horizontal towards the vertical, to at least its balanced position on the base before the auxiliary leg can be conveniently released and moved from its extended position towards its folded position.

The disposition of the locking arm is also such that when the bed frame is raised towards the vertical to an extent to permit convenient access to the lock releasing means on the auxiliary leg, this arm will engage the lock pin on the bed frame and force the frame to a vertical position as the auxiliary leg is drawn inwardly to folded position.

A further feature of the present invention is the provision of means for latching the auxiliary leg in either extended or partially extended position. This provides in a greatly simplified structure, means for preventing collapsibility of the auxiliary leg towards the base by the unbalanced weight of the frame thereon when the frame is pulled down towards the horizontal and before the auxiliary leg has been moved to its fully extended position.

The merits of my improvement are more fully set forth in the following specification, reference being made therein to the accompanying drawings, wherein, I have illustrated my preferred specific embodiment.

In these drawings:

Fig. 1 is a fragmentary front elevation of my bed structure, illustrating the bed frame in its vertically disposed position on the base and the auxiliary leg in its folded position;

Fig. 2 is a sectional plan view taken as indicated by the line 2—2 of Fig. 1;

Fig. 3 is an enlarged, fragmentary, detailed plan view, taken as indicated by the line 3—3 of Fig. 1, showing the auxiliary leg in folded position;

Fig. 4 is a detailed view similar to Fig. 3, illustrating the auxiliary leg in extended position;

Fig. 5 is a fragmentary, detailed view taken as indicated by the line 5—5 of Fig. 3; and,

Fig. 6 is a small, diagrammatic side eleva-

tion, illustrating vertical movement of the bed frame.

Referring first to Figs. 1 and 2, the numeral 10 designates generally a base movably supported upon a plurality of rollers 11. The base is composed of arcuate end members 12, a rear transverse brace member 13 and a front transverse brace member 14. The end members 12 are made arcuate to facilitate movement of the base into and out of small recesses, such as closets and through doors of substantially standard widths. The rollers 11 may be rigid or of the caster type.

Standards 15 are rigidly supported upon the base 10 adjacent the forward ends of the end members 12 and uprights 16 are mounted upon the rear ends of these members, which are suitably joined to form the head of the bed. A bed frame 17, carrying suitable springs 18, is pivotally mounted upon the standards 15, through the medium of pivot pins 19, carried by the latter.

As illustrated in Fig. 1, pivotal connections between the standards 15 and frame 17 are adjacent the head end of the frame, so that the head end overhang is substantially equal to the height of the standards 15 above the base 10. Brace members 20 may be provided between the standards 15 and uprights 16 lending rigidity to the base structure.

A plurality of contractile, helical springs 21 are each connected at one end to a transversely disposed brace member 22, carried by the side frame members 17 and at their opposite ends to the transverse base member 14 of the base 10. These springs I have termed as "balance springs" for the reason that they are provided to normally hold the bed frame 17 in its vertically disposed position, as illustrated in Fig. 1, and to minimize the physical effort required to raise and lower this frame upon the base 10, between its vertical and horizontal positions, as diagrammatically illustrated in Fig. 6. Any number of these springs may be provided to obtain the desired cushioning effect and their tensile strength is arranged in accordance with the size of the bed, the weight of the frame 17 with its springs 18 and the usual amount of bedding.

An auxiliary leg 23, preferably formed of converging arms 24 and 25, is pivotally mounted upon the base 10; the arm 25, being pivotally joined to a plate 26, by means of a pin 27, and the arm 24 likewise joined to a plate 28 by means of a pivot pin 29. Plate 26 is carried by a transverse brace member 30, supported between standards 15, and plate 28 is carried by the transverse brace member 14. Pins 27 and 29 are necessarily co-axial and their common axis is tilted slightly from the vertical, as illustrated in Fig. 1, sufficient to raise the swinging end of the auxiliary leg free of the floor when in folded position and for bringing it into engagement with the floor when in its fully

extended position. If desired, a suitable roller or caster wheel 31 may be provided on the outer leg 23. To form a rigid structure a brace rod 32 joins the divergent ends of the arms 24 and 25.

5 A contractile helical spring 33 is secured at one end to a member 34, supported on one flange of the transverse brace member 14, and at its opposite end to the arm 24 of leg 23, adjacent to and forward of its pivot pin 29. This spring is disposed (see Figs. 2, 3 and 4) on one side of pivotal axis of the leg 23, and is always under tension to move the auxiliary leg 23 from its extended position, as illustrated in Fig. 4, to its folded position as illustrated in Fig. 3, and to always normally hold the leg in folded position. While the tensile strength of the spring 33 is sufficient to hold the leg 23 in folded position, or to move it to 10 that position from its extended position, it is not of sufficient strength to greatly interfere with its manual movement outwardly to its extended position.

20 An arcuate arm 35 is rigidly mounted on and carried by arm 24, of leg 23, to swing concentrically around the axis of pivot pin 29; being rigidly braced by means of a member 36. Upon movement of the leg 23, from the position illustrated in Fig. 3 to that shown 30 in Fig. 4, and vice versa, the arm will travel around the pin 29 as a center.

35 A downwardly extending pin 37 is carried by a plate 38 secured to the head end frame member 17^b, and is so arranged that when the bed frame 17 is in its vertically disposed position, as illustrated in dot-dash lines in Fig. 6, it will extend at right angles to the plane of movement of the arcuate arm 35. This is clearly illustrated in Fig. 3. It is 40 also positioned to traverse an arc in a vertical plane substantially on line with the auxiliary leg 23 when it is in extended position, as illustrated in solid and dotted lines in Fig. 4, and when in the position illustrated 45 in Fig. 3 to be encircled by the arcuate arm 35 when the leg 23 is in its folded position. By this arrangement the bed frame 17 is prevented from being tilted outwardly as illustrated diagrammatically in Fig. 6, until the 50 auxiliary leg 23 is moved from the folded position, illustrated in Fig. 3 to its extended position, as illustrated in Fig. 4; the length of the arm 35 being such that the pin 37 cannot pass its end 39 until the leg 23 has 55 reached its fully extended position as illustrated in Fig. 4.

The curvature of the end of the arm 35 from the point indicated by the line X in Figs. 3 and 4 (which is the point at which the pin 37 is at rest when the auxiliary leg 23 is in folded position) is such as to effect the most efficient cam action between these elements when the arm 35 is brought into engagement with the pin 37 and before the 60 frame 17 has been moved fully to its vertical

position on the base. The end of the arm 35 is also bent upwardly, from the point X shown in Fig. 3 to its outer end, to insure engagement of the pin 37 by this end in case the leg 23 is moved towards its folded position before the bed frame 17 is moved to its final vertical position. As the extreme end 39 of arm 35 is positioned to effect engagement with or around the rear of pin 37, at substantially the point where the bed frame 70 is just passing from its balanced position on the base to its unbalanced position during outward movement, and vice-versa, the function of the arm 35 is to insure full outward movement of the leg 23 before the bed frame 75 17 can be pulled down to unbalanced position and to insure full upward movement of the bed frame to the vertical, before it can be moved to folded position.

80 As may be later explained, the position of the latching means for holding the leg 23 in an extended position is such that it cannot be reached for releasement, to permit folding of the auxiliary leg, until the bed frame 17 has been moved within the zone of its balanced position on the base, as substantially indicated by the dotted line in Fig. 6. When in this position movement of the auxiliary leg from the position as illustrated in Fig. 4 to that illustrated in Fig. 3 will cause the 85 arm 35 to engage around the pin 37 (the upwardly tilted extreme end of the arm reaching the pin 37 in its higher position) which will, when further inward movement of the auxiliary leg is effected by the action 90 of the spring 33, tend, through the cam action resulting from the engagement of arm 35 around pin 37, throw the bed frame 17 to the vertical. In other words, the leg 23 cannot be collapsed when the bed frame is 95 at an angle, relative to the base, to be in unbalanced or unsafe position. This, of course, takes into consideration inaccessibility of the lock latch for manipulation until the bed frame 17 is nearing its balanced position on 100 the base, this matter being taken into consideration in determining the length, curvature and upward tilt of the end of the arm 35. Thus the curvature of arm 35 is such that it will move substantially eccentric to the 105 pin 37 when the latter is in the position illustrated in Fig. 3.

110 The above described arrangement also obviates possibility of the leg 23 being closed to folded position before the pin 37 is within 115 the zone of movement of the arm 35, and when the frame 17 is in unbalanced position on the base.

120 As hereinbefore stated, the auxiliary leg 23 is held normally in folded position, as illustrated in Fig. 3, and moved to that position, from the position illustrated in Fig. 4, by the action of spring 33. The leg 23 is held outwardly in either extended or intermediate extended position by means of 125 130

a latch bar 40. This bar is pivotally supported upon the lower end of a bolt 41 extending through the leg 23; the bolt extending loosely through an aperture therein to permit substantially universal movement. The bar is twisted, as shown, to present a horizontally disposed flat extended end 42, and a substantially vertically disposed opposite end 43. The end 42 is positioned comparatively close to the pivot pin 29 of the leg 23 and is arranged to be engaged by the foot to tilt the opposite end of the bar upwardly against its weight. The end 43 of the bar 40 extends through an aperture 44 in a plate 45, depending from the transverse brace member 14, as illustrated in Fig. 5. The aperture 44 is of a size to permit certain freedom of movement of the bar therein to allow for the arcuate movement of its opposite pivoted end.

The lower edge of the end 43 is serrated as at 46; the serrations being arranged to engage the plate 45 at the lower end of the slot 44 to hold the leg 23 outwardly against the action of the spring 33. The serrated edge 46 is always in engagement with the lower end of the slot 44 due to the weight of the end 43. As the leg 23 is adapted to be moved from the position illustrated in Fig. 4 to that shown in Fig. 3 by the foot, it is sometimes necessary to shift the body in effecting its full outward movement. Consequently, when pressure is relieved on the leg 23 to shift the body engagement of the bar 40 with plate 45 will prevent its collapsing by the action of the spring, 33. As arm 35 may be arranged to permit the bed frame 17 to be pulled downwardly to approximately the limit of its balanced position on the base, before the leg 23 is moved to the limit of its outward position, and as when the bed frame is in this position only a slight additional pull thereon may be necessary to overbalance the entire structure, it is important to provide the locking means, as the bar 40, to prevent collapsibility of the leg if it happens to be in an intermediate position. This is also true when the bed is being raised from the horizontal to a vertical position, as it has been proved by experience that in some cases there is a tendency of the operator to release or attempt to move the leg 23 inwardly to its folded position before the bed frame has been moved to the limit of its vertical position. Consequently, I have provided the arcuate arm of the form and length shown and have also provided lock bar 40 positioned adjacent the axis of the leg 23, making this inconvenient to be reached until the bed is in substantially its balanced position, thus insuring comparatively safe handling of the structure.

Having described my invention, I claim:

1. A folding bed, comprising a base, a bed frame pivotally mounted on the base to swing vertically thereon and overhang the base

when in horizontal position, an auxiliary leg pivotally mounted on the base and arranged to swing horizontally thereon from folded position longitudinally of the base to extended position transversely of the base and beneath the overhanging portion of the bed frame, means to yieldingly hold the leg in folded position and catch means to hold it in extended position against the action of the yielding means, said catch means comprising a latch plate on the base, a latch bar pivotally mounted adjacent one end on the leg, the opposite end of said bar arranged to engage the plate and the bar being serrated along one edge to engage the plate and releasably hold the leg against the action of the yielding means.

2. A folding bed, comprising a base, a bed frame pivotally mounted on the base to swing vertically thereon, and overhang the base when in horizontal position, an auxiliary leg pivotally mounted on the base and arranged to swing horizontally thereon from folded position longitudinally of the base to extended position transversely of the base and beneath the overhanging portion of the bed frame, means to yieldingly hold the leg in folded position and catch means to hold it in extended position against the action of the yielding means, said catch means comprising a latch plate on the base, a latch bar pivotally mounted adjacent one end on the leg to permit vertical and horizontal movement and adapted to engage the plate along one edge, the plate engaging edge being serrated to hold the leg against the action of the yielding means, the bar being extended beyond its pivoted end to provide a toe plate for tilting it to effect its disengagement from the plate.

3. A folding bed, comprising a base member, a bed frame pivotally mounted on the base to swing vertically thereon and overhang the base when in horizontal position, an auxiliary leg member pivotally mounted on the base and arranged to swing horizontally thereon from folded position longitudinally of the base to extend position transversely of the base and beneath the overhanging portion of the bed frame, means to yieldingly hold the leg in folded position and catch means to hold it in extended position against the action of the yielding means, said catch means comprising a latch plate on one of said members, a latch bar pivotally mounted adjacent one end on the other of said members, the opposite end of said bar being serrated along one edge and arranged to releasably engage the plate to hold the leg against the action of the yielding means.

In witness that I claim the foregoing I have hereunto subscribed my name this 7th day of April, 1926.

EDGAR COCKS.
